UNITED STATES PATENT OFFICE.

WILLIAM G. BOOTH, OF WEST SOMERVILLE, MASSACHUSETTS, ASSIGNOR
TO WILLIAM UNDERWOOD COMPANY, OF BOSTON, MASSACHUSETTS, A
CORPORATION.

DESIGN FOR A BOX.

SPECIFICATION forming part of Design No. 36,785, dated February 9, 1904.

Application filed December 20, 1902. Serial No. 136,088. Term of patent 7 years.

To all whom it may concern:

Be it known that I, WILLIAM G. BOOTH, a citizen of the United States of America, and a resident of West Somerville, in the county of Middlesex and State of Massachusetts, have invented a certain new, original, and ornamental Design for a Box, of which the following is a full, clear, and exact description.

Reference is to be had to the accompanying drawings, in which—

Figure 1 is a plan view, Fig. 2 an end view, and Fig. 3 a side view, of the box, showing my new design.

What I claim is—

The ornamental design for a box herein shown.

WILLIAM G. BOOTH.
